19 Claims.

(Cl. 62—5)

This invention relates to the art of absorption refrigerating systems and more particularly to a novel control mechanism particularly designed for use therewith.

In prior absorption refrigerating apparatus it is customary to provide a constantly burning pilot for igniting the combustible fuel burner which heats the refrigerant vapor generator. In addition, some means must be provided for igniting the pilot initially and also for igniting the same in the event that it is accidentally extinguished. This possesses a number of disadvantages among which may be mentioned the necessity for auxiliary igniting apparatus and the necessity for a constantly operating burner which consumes an appreciable amount of fuel which does not measurably contribute to the operation of the system. The apparatus must be so designed and arranged that the generator and its associated burner can be positioned in the cabinet in a manner to permit the operator to obtain ready access to the burner and its associated pilot in order to ignite the same when necessary. The combined effect of these factors results in a decrease in the efficiency of the system, an increase in the operating cost thereof, a design of apparatus not ideally suited for arrangement within the cabinet, an appreciable waste of fuel and the incorporation in the system of auxiliary equipment which has no operative function with respect to the production of refrigeration and which is rarely used even though necessary.

Accordingly, it is a principal object of the present invention to provide a three-fluid absorption refrigerating system and associated control and burner mechanism which will eliminate the necessity for a constantly burning pilot which will eliminate the necessity for auxiliary manual igniting apparatus and which will permit the boiler and its associated burner to be positioned in any desired part of the cabinet construction without regard to its availability to the operator for igniting or other purposes, all of which contribute greatly to the production of an economical, efficient commercially acceptable unit.

It is a principal object of the invention to provide a refrigerating apparatus including a fuel burner for heating the boiler which is provided with an electrical igniting device connected in circuit with the circulating motor in such fashion that energization of the electric circuit by the control causes operation of the igniter and simultaneously admits fuel to the burner. By this means fuel is not admitted to the burner unless igniting conditions are met.

It is a further object of the present invention to provide an absorption refrigerating apparatus of the type utilizing a pressure equalizing medium circulator which apparatus includes a control and burner assembly so constructed and arranged that energization of the circulator, the supply of fuel to the burner and ignition of the gas are all simultaneously controlled in a simple efficient manner.

It is a still further object of the present invention to provide an apparatus of the character above referred to in which the fuel burner is opened to admit fuel to the burner simultaneously with energization of the inert gas circulator and in which a safety valve is maintained in open position after initial opening movement thereof by heat radiated from the generator heating unit after de-energization of the electrical starting apparatus.

It is another object of the invention to provide a fuel burner and ignition arrangement in which fuel is supplied to the burner only after energization of the igniting apparatus.

It is still another object of the present invention to provide a burner of the character above described in which the igniting apparatus is automatically de-energized and moved out of the path of flame issuing from the burner very shortly after ignition of the burner.

Other objects and advantages of the invention will become apparent as the description proceeds when taken in connection with the accompanying drawings in which:

Figure 1 is a partly diagrammatic and partly elevational sectional view of a three-fluid absorption refrigerating system embodying the present invention.

Figure 2 is a fragmentary rear elevational view of the apparatus shown in Figure 1.

Figure 3 is a partial sectional view on an enlarged scale of a burner and igniting apparatus.

Figure 4 is a schematic wiring diagram of the control mechanism.

Figure 5 is an elevational view partly in section of a modified form of the invention.

Figure 6 illustrates a detail of the apparatus disclosed in Figure 5.

Figure 7 is a view taken on the line 7—7 of Figure 6.

Referring now to the drawings in detail and first to Figures 1 and 2 thereof, there is disclosed a three-fluid absorption refrigerating system comprising a boiler B, an analyzer D, an air-cooled rectifier R, a tubular air-cooled condenser C, an evaporator E, a gas heat exchanger G, an

inclined tubular air-cooled absorber A, a liquid heat exchanger L, a solution reservoir S, and a circulating fan F which is driven by an electrical motor M. These elements are suitably connected by various conduits to form a complete refrigerating system including a plurality of gas and liquid circuits to which reference will be made in more detail hereinafter.

The above described refrigerating system will be charged with a suitable absorbent, such as water, a suitable refrigerant, such as ammonia, and an inert pressure equalizing medium, preferably a dense inert gas like nitrogen.

The application of heat to the boiler B generates refrigerant vapor therefrom which passes upwardly through the analyzer D in contact with strong solution flowing downwardly therethrough. The refrigerant vapor is conveyed from the analyzer D to the upper portion of the condenser C by means of a conduit 11 which includes the air-cooled rectifier R. The refrigerant vapor is liquefied in the condenser C and is conveyed therefrom to the bottom portion of the evaporator E by means of the conduit 12 which includes a downwardly extending U-shaped loop portion 13 to form a pressure balancing liquid column. The condenser side of the loop 13 is vented to the rich gas side of the gas heat exchanger G by means of a conduit 14.

The lean solution which is formed in the boiler by the generation of refrigerant vapor is conveyed therefrom to the solution reservoir S by way of the conduit 16, the liquid heat exchanger L, and a conduit 17 which includes a loop portion provided with air-cooling fins to form a solution pre-cooler. The lean solution is elevated from the reservoir S into the upper portion of the absorber A by means of a gas lift pump conduit 19.

Pumping gas is supplied to the lower portion of the conduit 19 by means of a conduit 20 which connects to the discharge conduit 21 of the circulating fan F. The reservoir S is vented by means of a vent conduit 22 to the suction inlet conduit 23 of the circulating fan F.

The absorption solution elevated into the conduit 19 flows downwardly through the absorber in counterflow relationship with an inert gas refrigerant vapor mixture flowing upwardly therethrough. The absorption solution absorbs refrigerant vapor from the mixture in the absorber and the heat of absorption is rejected to cooling air flowing over the fins mounted on the exterior walls of the absorber conduit.

The strong solution formed in the absorber is conveyed from the bottom portion thereof to the upper portion of the analyzer D by means of the conduit 25, the liquid heat exchanger L, and the conduit 26, thus completing the absorption solution circuit.

The lean inert gas formed in the absorber is conveyed from the upper portion thereof into the suction inlet of the fan F by the conduit 23. The lean gas is then placed under pressure by the fan F and is conveyed therefrom to the bottom portion of the evaporator E by means of the conduit 21, the gas heat exchanger G, and the evaporator inlet conduit 27.

The evaporator E is shown diagrammatically herein and it may take any desired form of construction. However, a preferred construction is disclosed and claimed in the co-pending application of Curtis C. Coons and William H. Kitto, Serial No. 386,196, filed April 2, 1941, now Patent No. 2,328,196, dated August 31, 1943.

The evaporator is constructed of relatively small diameter tubing whereby the inert gas travels therethrough with a velocity sufficient to sweep or drag the liquid refrigerant through

5 all portions thereof as it is evaporating. The evaporator is also provided with an enlarged diameter finned box-cooling conduit 28, which is tilted slightly rearwardly in order that the liquid refrigerant may flow therethrough by gravity 10 as the velocity of the gas stream in the box-cooling conduit is insufficient to propel the refrigerant. The rich gas formed in the evaporator is conveyed from the box-cooling conduit 28 to the bottom portion of the absorber A by 15 means of the conduit 29, the gas heat exchanger G, and the conduit 30. A suitable overflow drain 31 is connected between the bottom portion of the evaporator E and the strong solution return conduit 25.

20 As may be seen clearly in Figure 1, the above described apparatus is associated with a cabinet which comprises an insulated refrigeration chamber 33 overlying a mechanism chamber 34. The cabinet also includes a rear vertical air-cooling flue 35. Cooling air may be admitted to the compartments 34 and 35 in any desired manner as by louvres in the rear walls of the compartment 35 and in the bottom wall of the compartment 34.

25 30 The refrigerating apparatus will be mounted upon a suitable frame (not shown) which will be associated with the cabinet construction and will be secured thereto.

35 The arrangement of the apparatus with respect to the cabinet will now be described. The boiler B is positioned in the chamber 34 directly beneath the flue 35 at the rear lower corner of the cabinet assembly.

40 The tubular inclined absorber A extends forwardly and downwardly from a position directly beneath the bottom portion of the flue 35 and into the compartment 34. The rectifier and condenser are positioned at the intermediate and upper portions of the flue 35, respectively. The 45 evaporator is positioned within the compartment 33 and the gas heat exchanger is embedded in the insulation of the rear wall thereof.

45 As is illustrated in Figures 1 and 2 the boiler analyzer liquid heat exchanger assembly is 50 encased in a suitable block of insulating material indicated generally at 37. The boiler is provided with a central flue 38 which communicates with a products of combustion discharge conduit 39 extending upwardly to the top portion of the flue 55 35 and in one extreme corner thereof. This prevents hot products of combustion from interfering with the cooling of the various parts of the system.

55 A control mechanism for the apparatus is indicated generally at 40 which will be responsive to thermal conditions at the evaporator or within the space 33 as may be desired. The control mechanism 40 is supported on a suitable framework indicated generally at 41 and is provided

60 65 with a regulating dial 42 positioned in a recess 43 formed in a closure panel 44 for the compartment 34. The mechanism 40 may be of any desired type, a preferred construction being disclosed in my co-pending application, Serial No. 148,424, filed June 16, 1937, now Patent No. 2,228,343, dated January 14, 1941.

70 75 The mechanism 40 will include a simple switch for controlling the energization of the motor M which drives the circulating fan F and it also operates a gas valve 45 which is carried by the

mechanism 40. Gas is supplied to a burner 46 which is positioned to heat the boiler B, as will be disclosed in more detail hereinafter, by means of a conduit 47 passing through the valve 45.

Referring now more particularly to Figures 3 and 4 the construction of the gas burner and igniter assembly will be described.

The gas burner, igniter and valve assembly 46 is supported from the insulating block 37 by a suitable bracket 48 which is attached to the main burner casting 50. The casting 50 is provided with an internal bore which receives a valve seat plug 51 which is provided with a valve seat 52 facing the gas inlet conduit 47. The valve seat 52 communicates with an annular passage 53 formed therearound by means of a central bore 54 and radial passageway 55. The annular passageway 53 communicates with the laterally extending duct 56 formed in a portion of the casting 50. The valve seat plug 51 is threadedly received by the main casting 50 and a suitable gasket 60 is provided at the joints therebetween to prevent gas leakage.

The valve seat 52 is designed to cooperate with a valve element 57 which is carried by an actuating shaft 58 passing through the valve seat element 51.

The lower end of the shaft 58 is suitably secured and sealed to a snap-acting thermostatic disc element 61. The outer edges of the disc 61 are crimped and sealed into a supporting cup 62 which is carried by the valve seat plug 51 and is secured thereto by means of a nut and sealing gasket indicated at 63. A suitable arcuate shielding disc 64 is also secured in the supporting cup 62 and is provided with a central opening through which passes an actuating cap 65 of insulating material which is carried on the lower end of the shaft 58.

The end of the passageway 56 remote from the valve plug 51 is threaded and receives a metering orifice plug 68 which is adjusted by means of a needle valve 69 also threadedly mounted in the extension 56. A downwardly extending duct 70 extends from the conduit 56 beyond the metering plug 68.

A burner tube 72 is threadedly mounted on a nipple 73 on the lower end of the conduit 70. The nipple 73 and the lower end of the conduit 70 are provided with a central bore 74 which communicates with the burner tube 72. A gas jet plug 75 is threadedly received in the burner end of the bore 74 to project the gas into the central portion of the tube 72.

The tube 72 is provided with a suitable primary air inlet 76 adjacent the nozzle plug 75. A primary air control sleeve 77 is rotatably mounted on the exterior wall of the burner tube 72 adjacent the nozzle plug 75 in order to regulate the size of the opening 76. The rotatable sleeve 77 also carries a sleeve 78 which extends to the end of the burner tube 72 and in concentric relationship therewith whereby to provide a primary air duct which will bring air from the area at the end of the burner tube and will prevent pressure differentials from occurring between the nozzle 75 in the end of the burner tube 72.

The end of the burner tube 72 carries a shield 79 which has a plurality of spacing tongues 80 (only one shown) bearing against the inner wall of the sleeve 78 to maintain the proper space relations between the burner tube and the air sleeve.

The burner tube 72 is provided with a struck-up portion 81 which abuts an end portion of the

sleeve 77 in order to maintain the same in proper relationship with the burner tube. A small spring washer 82 is positioned between the conduit 70 and the adjacent ends of the sleeves 77 and 78 in order to maintain a frictional engagement between the ends of the sleeve 77 and the small tongue 81. The size of the primary air opening 76 is thereby adjustable simply by turning the outer sleeve 78 which is rigidly attached to the control sleeve 77.

In order to provide heat to actuate the snap acting disc initially in a manner to move the valve 57 to open position, an electrical heating unit of the so-called "Calrod" type is wrapped around the supporting cup 62 for the disc 61. The heating unit is shielded by means of a refractory cup 85 which is constructed of porcelain or similar material. The cup 85 is held in position between the base portion of the cup 62 and a gasket 86 which rests upon a shoulder formed on the valve plug body 51.

In order to maintain the disc in open position after the heating unit 84 has been de-energized a heat conducting finger 88 is clamped to the outer edge of the cup 62 and extends downwardly adjacent the end of the tube 72 in position to be heated by flame issuing from the tube 72. In this way heat is conducted from the flame through the finger 88, the disc 61 to maintain the same in upwardly flexed position; that is, in the position opposite that illustrated in Figure 3 whereby to maintain the valve plug 57 away from the seat 52 to permit gas to flow to the burner tube 72.

In order to ignite the burner 72 a loop ignition wire 90 is mounted adjacent the end of the tube 72. The coils 90 rest upon a refractory support 91 which is constructed of porcelain or similar material and the ends of the element 90 are secured by electrical conducting bolts 92 which pass through the refractory 91. The refractory 91 is supported by an arm 94 carried by the main casting 50. Electrical contact between the arm 94 and the conducting bolts 92 is prevented by means of shoulders 95 on the refractory 91 which pass through openings in the support 94. A sheet of mica or similar material 96 is interposed between the securing and contacting nuts on the bolts 92 and the support 94.

The energization of the heating element 84 and of the ignition element 90 is under the control of a switch mechanism indicated generally at 97. The switch mechanism is suitably supported on an extension 98 of the conduits 56 and 70 and includes a pair of switch arms 99 and 100 normally supported in spaced relation. The switch arms 99 and 100 are supported from the element 98 and are insulated therefrom by well known construction. The upper and longer arm 99 extends into the path of movement of the cap 65 which is carried on the end of the shaft 58. The arrangement is such that movement of the valve plug 57 into sealing relation with the valve seat 52 to discontinue the supply of fuel to the burner tube 72 causes the cap 65 to urge the switch arm 99 downwardly, as viewed in Figure 3, into contact with the switch arm 100.

Referring now to Figure 4 the operating circuits of the apparatus will be described. Electrical energy is supplied to the apparatus from a pair of conductors 104 and 105. The conductor 104 connects directly to the contact arm 99 and also to the circulating motor by means of the conductor 106. The contact arm 100 of the switch

97 connects directly to one side of the igniting loop 90 and to the heating element 84 by means of a conductor 107. The other sides of the loop 90 and of the heating coil 84 are connected to the control mechanism 40, which includes an electrical switch, by means of conductors 108 and 109, respectively. The motor is also connected to the conductor 109 by means of a conductor 110. The control 40 is connected directly to the line wire 105.

The operation of this form of the invention is as follows: Assuming that there is a demand for refrigeration the thermostatic mechanism within the box 40 will actuate the gas valve 45 to open position whereby gas will be supplied to the safety control valve 57. The mechanism 40 will also close the circuit between the conductors 105 and 109. This will immediately energize the circulating motor M whereby the inert gas will be circulated by the fan F.

As the valve 57 will be in engagement with the seat 52 the switch contacts 99 and 100 will be in engagement whereby the heating coil 84 and the igniting loop 90 will also be energized. A few seconds after energization of the heating coil 84 the heat generated thereby will stress the thermostatic disc 61 sufficiently to cause the same to snap upwardly, as viewed in Figure 3, to disengage the valve plug 57 from the seat 52 whereby fuel will be supplied to the burner 72. Slightly before the disc 61 has actuated the valve to open position, the igniting loop 90 will have become incandescent and will ignite the gas issuing from the end of the burner tube 72. Immediately the valve 57, 58 is snapped to the open position the contacts 99 and 100 move to open position and de-energize the heating coil 84 and the igniting loop 90. However, there is sufficient heat in the valve assembly to maintain the disc 61 in valve opening position until the heat conducted from the flame through the finger 88 is sufficient to maintain it in that position as long as the flame is present on the burner 72. Likewise the residual heat in the incandescent igniting loop 90 is sufficient to maintain the same in incandescent igniting condition for the small fraction of a second required for the gas to pass from the valve seat 52 to the flame shield 79 of the burner tube 72.

This construction entirely dispenses with the cost of the constantly burning pilot and the need for manual ignition for the boiler heating burner and its pilot. By this construction the burner is supplied with fuel only after energization of the igniting loop wherefore ignition is positively assured. It is also worthy of note that the igniting circuits are broken immediately the safety valve moves to open position whereby any failure of flame at the burner 72 will cause rapid closure of the safety valve by the thermostatic disc 61 to prevent the escape of raw gas from the burner tube. This provides a repeating igniter in the event of failure of ignition at the burner. Should the fuel fail to ignite for any reason after energization of the starting coil 84, the valve will remain in open position for a very short period of time only before the thermostatic disc returns it to closed position. The quantity of unburned fuel which could escape in this period of time is too small to create a dangerous condition. Assuming failure of ignition the igniter and starting coil would be re-energized immediately the valve closed and a new starting and igniting cycle would be initiated.

Referring to Figures 5 to 7, there is disclosed 75 158 and 159 are in contact with the buttons 169

a modified form of the invention. Certain portions of this apparatus are identical with portions described in connection with Figures 1 and 2 and are given the same reference characters primed. Except as is indicated in Figures 5, 6 and 7 this form of the invention is identical with that previously described and is designed and intended to be utilized with the same type of refrigerating system and in the same general environment. Therefore, only the burner, igniter and control system have been illustrated as they are the only portions which differ in any way from those described in Figures 1 to 4.

In this form of the invention the control mechanism 150 operates an electrical switch only. 15 Gas is supplied to the burner 78' by means of the conduit 151 in which there is interposed a solenoid control valve 152.

The burner construction does not include a safety cut-off valve as that function is performed 20 by the solenoid valve and its controls. The conduit 151 merely connects directly into a supporting housing 155 which includes a suitable conduit connected to the nozzle of the burner assembly. 25 The burner and associated housing 155 are supported from the boiler insulation by means of a bracket 156 which positions the burner to discharge the products of combustion into the boiler flue 38'. A block of insulating material 157 is 30 suitably supported upon the bracket 156 and at its upper end carries a laterally spaced pair of U-shaped electrical conductors and switch contacts 158 and 159 which are made of spring material.

The U-shaped spring switch contacts 158 and 159 are attached to the block of insulating material 157 by means of attaching and connecting bolts 161 which pass through the arms of the switch contacts 158 and 159 adjacent the bight portions thereof and through spacing blocks of insulating material 160.

A thermostatic bar 165 is suitably supported upon the insulating block 157 between the switch arms 158 and 159. A sheet of mica or similar material 166 is attached to the extending end 45 of the thermostatic element 165. A loop igniting wire 167 has its ends attached to laterally extending wings 168 of the mica 166. The wings 168 extend between the ends of the resilient U-shaped switch elements 158 and 159 and carry 50 contacting rivet elements 169 to which the ends of the wire 167 are attached and which are positioned to contact the upper arms of the U-shaped resilient switches 158 and 159 on opposite sides of the thermostatic bar 165.

An electrical conducting bar 170 is rigidly secured to the thermostatic bar 165 by means of a pair of rivets 171 which also serve to secure the mica. The conducting bar 170 is insulated from the thermostatic strip by means of a strip of insulating material 172. The outer ends of the bar 170 are provided with protuberances 173 which are positioned to contact the lower arms of the U-shaped resilient switching elements 158 and 159.

As can be seen in Figure 5, the outer ends of the thermostatic bars 165 and the igniting loop which is carried thereby are positioned slightly beyond the end of the burner and when cool the thermostatic bar flexes upwardly in the position shown in Figure 5 to bring the loop 167 into the path of flow of fuel issuing from the end of the burner whereby to ignite the same. In this position the upper arms of the switching elements 70 75 158 and 159 are in contact with the buttons 169

and are flexed upwardly as is illustrated in Figures 5 and 6. In this position also the protuberances 173 are raised from and are out of contact with the lower arm of the U-shaped switching element.

Electrical energy is supplied to the apparatus from a pair of supply conductors 175 and 176. The conductor 175 connects directly to the switch arm 159 and to the motor M' by means of a conductor 177. The conductor 176 connects to the thermostatic mechanism 150 which in turn is connected to the solenoid valve and to the circulating motor by means of conductors 178 and 179, respectively. The solenoid valve is connected to the switch arm 158 by means of an electrical conductor 180.

The operation of this form of the invention is as follows: Assume that the temperature conditions of the refrigerator are such that the control mechanism 150 has broken the circuit between the lines 176 and 178. The thermostatic element 165 will be relatively cool and will be flexed upwardly into the position illustrated in Figures 5 and 6. When the temperature of the refrigerator rises in response to demand for refrigeration, the thermostatic mechanism 150 will close the circuit between the conductors 176 and 178. The circulating motor will immediately be energized through the following circuit 176, 150, 179, 177 and 175. The solenoid valve will be moved to open position and the igniting loop 167 will be energized as follows: 176, 150 and 178, 180, 158, 169, 167, 169, 159 and 175. Energization of the solenoid valve will cause fuel to be supplied to the burner which will be ignited by the incandescent loop 167 immediately it issues therefrom. Shortly after ignition of the fuel supplied to the burner the combined heat of the incandescent wire and of the burner will heat the thermostatic element 165 and will cause the same to flex downwardly, as viewed in Figures 5 and 6, which will break the engagement between the upper arms of the switch elements 158 and 159 and the contact buttons attached to the ignition wire 167. However, the circuit will be maintained closed by engagement between the conductor 170 and the lower arms of the switching elements 158 and 159. Therefore, the net result of the downward flexing of the thermostatic element 165 is to remove the igniting loop from the path of the flame issuing from the burner in order to protect the same from deleterious effects of constant exposure to flame and to deenergize the igniting loop 167 without, however, de-energizing the solenoid valve as the circuit between the elements 158 and 159 is maintained by the cross-arm conductor 170.

In accordance with this form of the invention like that previously described, fuel cannot be supplied to the burner unless the igniting loop is energized and failure of flame at the burner will immediately cause the thermostatic element upon which the igniting loop is mounted to flex to a position to energize the igniting loop. In the event of current failure which would prevent energization of the igniting loop, no gas could be supplied to the burner as it will be impossible to energize the solenoid valve 152. In short, this form of the invention provides an arrangement in which it is impossible to supply fuel to the burner unless the igniting device is conditioned for energization.

The present invention provides an absorption refrigerating system in which the boiler and its associated burner assembly may be positioned in

any part of the cabinet without regard to the accessibility of the burner for ignition by the operation. In addition, it is impossible for raw gas to escape from the burner under any condition of operation and no loss is sustained by maintaining a continuously operating pilot burner and its associated manual ignition mechanism.

The absorption refrigerating apparatus and its associated control disclosed herein provides a unique integration of the various pieces of apparatus in such fashion that the normally controlling gas valve, the safety cut-off valve of the burner and the ignition mechanism thereof are all under the direct control of the refrigeration demand regulating mechanism.

A feature of peculiar advantage resident in the instant invention results from the fact that the normal control mechanism for the refrigerating apparatus has direct control of the energization and ignition of the fuel burner after which the ignition mechanism is de-energized without permitting the escape of raw gas from the burner and without interfering with the control exercised by the refrigeration demand responsive mechanism over the fuel burner.

A most compact and efficient form of construction of the apparatus is rendered possible by the arrangement herein disclosed because the boiler and its immediately associated mechanism may now be placed in a portion of the apparatus remote from the front of the cabinet and directly beneath the cooling flue whereby compactness of the assembly is promoted and the lengths of the various conduits interconnecting the various elements is reduced to a minimum. This is materially advantageous both from the constructional and functional viewpoints for obvious reasons.

While various forms of the invention have been illustrated and described in considerable detail, it is to be understood that the applicant is not to be limited to the precise construction shown as various changes may be made in the construction, proportion and arrangement of parts without departing from the spirit of the invention or the scope of the appended claims.

I claim:

1. Absorption refrigerating apparatus comprising an inert gas circuit including an evaporator and an absorber, a solution circuit including a boiler and said absorber, power driven means for circulating the inert gas through said inert gas circuit, a fuel burner arranged to heat said boiler, fuel supply means for said burner, electrical igniting means for said burner, refrigeration demand responsive means for controlling the energization of said power driven inert gas circulator and of said electrical igniting means, and means controlling said fuel supply means arranged to be operated to fuel supplying condition only when said igniting means has been energized by said refrigeration demand responsive means.

2. Absorption refrigerating apparatus comprising an inert gas circuit including an evaporator and an absorber, a solution circuit including a boiler and said absorber, power driven means for circulating the inert gas through said inert gas circuit, a fuel burner arranged to heat said boiler, fuel supply means for said burner, electrical igniting means for said burner, refrigeration demand responsive means for controlling the energization of said power driven inert gas circulator and of said igniting means, means controlling said fuel supply means arranged to be operated to fuel supplying condition only when

said igniting means has been energized by said refrigeration demand responsive means, and means for de-energizing said igniting means after initial energization thereof without de-energizing said power driven circulator.

3. Absorption refrigerating apparatus comprising an inert gas circuit including an evaporator and an absorber, a solution circuit including a boiler and said absorber, power driven means for circulating the inert gas through said inert gas circuit, a fuel burner arranged to heat said boiler, fuel supply means for said burner, igniting means for said burner, refrigeration demand responsive means for controlling the energization of said power driven inert gas circulator and of said igniting means, means controlling said fuel supply means arranged to be operated to fuel supplying condition only when said igniting means has been energized by said refrigeration demand responsive means, and means responsive to ignition of said burner for maintaining said fuel supply control means in fuel supplying condition.

4. Absorption refrigerating apparatus comprising an inert gas circuit including an evaporator and an absorber, a solution circuit including a boiler and said absorber, power driven means for circulating the inert gas through said inert gas circuit, a fuel burner arranged to heat said boiler, fuel supply means for said burner, igniting means for said burner, refrigeration demand responsive means for controlling the energization of said power driven inert gas circulator and of said igniting means, means controlling said fuel supply means arranged to be operated to fuel supplying condition only when said igniting means has been energized by said refrigeration demand responsive means, means for de-energizing said igniting means after initial energization thereof without de-energizing said power driven circulator, and means responsive to the presence of a flame on said burner for moving said igniting means away from such flame.

5. Refrigerating apparatus comprising a cabinet including an insulated storage compartment and a mechanism compartment, an absorption refrigerating apparatus including a generator in said mechanism compartment and a cooling unit in said storage compartment, a fuel burner arranged to heat said generator and not readily accessible from the exterior of said cabinet, an electrical igniting device for said fuel burner, and refrigeration production control means for controlling the supply of fuel to said burner and the operation of said electrical igniting device.

6. Absorption refrigerating apparatus comprising an inert gas circuit including an evaporator and an absorber, a solution circuit including a boiler and said absorber, means for liquefying refrigerant vapor produced in said boiler and for supplying the liquid to said evaporator, a fuel burner arranged to heat said boiler, fuel supply means for said burner, electrical igniting means for said burner, and refrigeration demand responsive means for controlling the supply of fuel to said burner and the operation of said electrical igniting means.

7. Absorption refrigerating apparatus comprising an inert gas circuit including an evaporator and an absorber, a solution circuit including a boiler and said absorber, means for liquefying refrigerant vapor produced in said boiler and for supplying the liquid to said evaporator, a fuel burner arranged to heat said boiler, fuel supply means for said burner, a safety cut-off valve in said fuel supply means, a thermostat positioned

to be heated by said burner for maintaining said safety cut-off valve in closed position when not heated, an electrical heater for heating said thermostat, an electrical igniter for said burner, and refrigeration control mechanism for governing the energization of said electrical heater and said igniter.

8. Absorption refrigerating apparatus comprising an inert gas circuit including an evaporator and an absorber, a solution circuit including a boiler and said absorber, means for liquefying refrigerant vapor produced in said boiler and for supplying the liquid to said evaporator, a fuel burner arranged to heat said boiler, fuel supply means for said burner, a safety cut-off valve in said fuel supply means, a thermostat positioned to be heated by said burner for maintaining said safety cut-off valve in closed position when not heated, an electrical heater for heating said thermostat, an electrical igniter for said burner, refrigeration control mechanism for governing the energization of said electrical heater and said igniter, means for deenergizing said electrical heater and said igniter after a period of energization thereof sufficient to open said valve and to ignite fuel issuing from said burner.

9. Absorption refrigerating apparatus comprising an inert gas circuit including an evaporator and an absorber, a solution circuit including a boiler and said absorber, means for liquefying refrigerant vapor produced in said boiler and for supplying the liquid to said evaporator, a fuel burner arranged to heat said boiler, fuel supply means for said burner, a solenoid valve controlling the flow of fuel to said burner, an electrical igniter for said burner, refrigeration demand responsive means for governing the operation of said valve and of said igniter, and flame responsive means for de-energizing said igniter after ignition of said burner.

10. Absorption refrigerating apparatus comprising a boiler, a power operated fluid circulator, a fuel burner arranged to heat said boiler, fuel supply means for said burner, electrical igniting means for said burner, refrigeration demand responsive means for controlling the energization of said power driven circulator and of said igniting means, and means controlling said fuel supply means arranged to be operated to fuel supplying condition only when said igniting means has been energized by said refrigeration demand responsive means.

11. Absorption refrigerating apparatus comprising a boiler, a power driven fluid circulator, a fuel burner for heating said boiler, fuel supply means for said burner, a valve in control of said fuel supply means, a thermostatic refrigeration demand responsive means in control of said valve and said circulator, an electrical igniter for said burner under the control of said thermostatic means, and means for discontinuing operation of said electrical igniter without affecting said burner after said igniter and said fuel supply valve have been operated by said control means.

12. In combination, a power operated fluid circulator, a fuel burner, an ignition means for said burner, condition responsive means for governing the energization of said fluid circulator and of said ignition means, means adapted to be energized by said condition responsive means for supplying fuel to said burner coincident with the energization of said ignition means, and means energized by the heat of said burner for maintaining the supply of fuel to said burner after ignition thereof.

13. In combination, a power operated fluid circulator, a fuel burner, an ignition means for said burner, condition responsive means for governing the energization of said fluid circulator and of said ignition means, means adapted to be energized by said condition responsive means for supplying fuel to said burner coincident with the energization of said ignition means, and means energized by the heat of said burner for maintaining the supply of fuel to said burner after ignition thereof, and for de-energizing said ignition means without de-energizing said fuel burner and said fluid circulator.

14. In a refrigerating apparatus of the absorption type; a generator, an evaporator, a condenser, an absorber and a power driven fluid circulator connected in circuit; a gas burner for heating said generator, a valve for controlling the supply of gas to said burner, thermostatic means arranged to be heated by said burner and to operate said valve to prevent the supply of gas to said burner when cold, an electrical heating device arranged to heat said thermostatic means to cause said thermostatic means to operate said valve to supply gas to said burner, refrigeration demand responsive means arranged to energize said electrical heating device, and said power driven fluid circulator, and means operated by said thermostatic means for de-energizing said electrical heating device when said valve has been operated to open position.

15. In a refrigerating apparatus of the absorption type; a generator, an evaporator, a condenser, an absorber and a power driven fluid circulator connected in circuit; a gas burner for heating said generator, a valve for controlling the supply of gas to said burner, thermostatic means arranged to be heated by said burner and to operate said valve to prevent the supply of gas to said burner when cold, an electrical heating device arranged to heat said thermostatic means to cause said thermostatic means to operate said valve to supply gas to said burner, an electrical igniter for said burner, refrigeration demand responsive means arranged to energize said electrical heating device and said electrical igniter and said power driven fluid circulator, and means operated by said thermostatic means for de-energizing said electrical heating device and said electrical igniter when said valve has been operated to open position.

16. In a refrigerating apparatus of the absorption type; a generator, an evaporator, a condenser, an absorber and a power driven fluid circulator connected in circuit; a gas burner for heating said generator, a valve for controlling the supply of gas to said burner, an electrical igniter for said burner, thermostatic means arranged to position said igniter adjacent said burner in igniting relationship therewith and to move said igniter away from said burner after ignition thereof, refrigeration demand responsive means arranged to open said valve and to energize said igniter and said power driven fluid circulator, and means actuated by said thermostatic means for de-energizing said igniter after ignition of said burner.

17. Absorption refrigerating apparatus comprising an inert gas circuit including an evaporator and an absorber, a solution circuit including a boiler and said absorber, power driven means for circulating the inert gas through said inert gas circuit, a fuel burner arranged to heat said boiler, fuel supply means for said burner, igniting means for said burner, a thermostatic valve arranged to be heated by said burner in control of the fuel supply to said burner, electrical heating means for said thermostatic valve, refrigeration demand responsive means arranged to govern the energization of said electrical heating means, said igniting means and said power driven circulating means, and means operable to de-energize said electrical heating means and said igniting means when said burner is ignited.

18. Absorption refrigerating apparatus comprising an inert gas circuit including an evaporator and an absorber, a solution circuit including a boiler and said absorber, power driven means for circulating the inert gas through said inert gas circuit, a fuel burner arranged to heat said boiler, fuel supply means for said burner, igniting means for said burner, a valve for controlling the supply of fuel to said burner, a thermostat arranged to open said valve when heated, electrical heating means arranged to heat said thermostat, a de-energizing switch in control of said electrical heating means and said igniting means, said deenergizing switch being arranged to be operated to open circuit position by said thermostat when heated, and refrigeration control means arranged to energize said electrical heating means, said igniting means and said power driven circulator in response to a demand for refrigeration.

19. Absorption refrigerating apparatus comprising an inert gas circuit including an evaporator and an absorber, a solution circuit including a boiler and said absorber, power driven means for circulating the inert gas through said inert gas circuit, a fuel burner arranged to heat said boiler, fuel supply means for said burner, igniting means for said burner, a valve for controlling the supply of fuel to said burner, a thermostat arranged to open said valve when heated, electrical heating means arranged to heat said thermostat, a de-energizing switch in control of said electrical heating means and said igniting means, said deenergizing switch being arranged to be operated to open circuit position by said thermostat when heated, and refrigeration control means arranged to energize said electrical heating means, said igniting means and said power driven circulator in response to a demand for refrigeration, and heat conducting means for conducting heat from said burner to said thermostat to maintain said valve in open position.
